UNITED STATES PATENT OFFICE

2,501,317

REMOVABLE TOWEL-BAR STRUCTURE

Michael A. Crozier, New York, N. Y.

Application November 4, 1947, Serial No. 784,063

6 Claims. (Cl. 211—86)

1

This invention relates to a demountable support for towels and the like.

An object of the invention is to provide a support of a simple and practical kind.

Another object of the invention is to provide such a support which is adapted to be fastened readily and securely to a support surface, such for example as the depending flange of a wash-bowl or lavatory, and which will assume a convenient and space-saving position.

Another object of the invention is to provide demountable support means for towels and the like which may be completely formed from metal stampings.

Another object of the invention is to provide support means of the above mentioned kind having arms and clamp means therefor in which each arm and clamp respectively is adapted to provide a three point grip on the support member.

Another object of the invention is to provide a device of the said kind having improved means for supporting clamps and for interconnecting cross bars between said arms.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawings, in which:

Figure 1 is a perspective view of a device embodying the invention applied to a support surface;

Figure 2 is an end view partly in cross section taken on the line 2—2 of Figure 1; and

Figure 3 is a plan view, partly in section and partly broken away, taken on the line 3—3 of Figure 2.

In the embodiment of the invention illustrated herein the device comprises the end arms 10 and 12, the cross bars 14 and 16, and the clamps 18. Each arm is stamped out of sheet metal with a notch *n* adjacent its rear end extending downwardly from the upper surface of the arm, and extended forwardly at the bottom thus leaving an abutment or contact face *f* defining the forward wall of the notch *n*, and adapted, when the device is secured on a support surface, to abut against the forward or outer

2

face of said surface. The wall *r* defining the rear wall of notch *n* may be slightly inclined upwardly and rearwardly and curved adjacent its top to facilitate guiding and fitting the edge portion of a support surface 20, such as the depending flange of a lavatory, into the notch.

At the rear ends of the arms 10 and 12 the inwardly extending flanges 22 and 24 respectively are provided on which the said clamps 18 are mounted. As illustrated each clamp is a U-shaped channel-like member comprising two parallel end portions *a* and *b*, and an intermediate portion *c*. The flanges 22 and 24 respectively and the said intermediate portions *c* of the clamp are each provided with holes through which screws *s* are inserted, preferably from the inside of the channel members. Thus the screws *s* are inserted from the front through the said holes in the flanges 22 and 24 respectively, and from between the arms *a* and *b* through the holes provided in said clamps 18 respectively, and on the threaded ends of the screws extending behind said flanges the wing nuts 26 respectively, are provided whereby the position of the clamps with respect to the arms 10 and 12 may be varied toward or away from the rear ends of the arms. It will be noted that the end portions or arms *a* and *b* of each clamp are sufficiently long so that they overlap the notch *n* in the arm to which the clamp is attached, and by adjustment of the wing nuts 26 the effective width of the notches may be varied to accommodate support surfaces 20 of different thicknesses.

It will also be noted that the front edges of the parallel portions *a* and *b* of each of clamps 18 are disposed on opposite sides of the arm 10 or 12 to which it is attached, and therefore on opposite sides of the contact face *f* defining the forward wall of a notch *n*, and so when the lower extremity of the support member 20 has been inserted in the notches *n* in said side arms, and the wing nuts 26 tightened, the said contact faces *f* will abut against the front face of the support surface 20 and the front edges of the parallel arms *a* and *b* of the clamps 18 will abut the rear surface of the support member 20, and the lines of contact of each clamp member 18 against the rear face of support surfaces 20 will be disposed laterally on opposite sides of the contact made between the front of the support surface and the contact face of the arm to which the clamp is attached.

The arms 10 and 12 are formed with the inwardly extending flanges 10^a and 12^a respectively, and to these flanges may be riveted or otherwise

secured the cross bar members 14 and 16 extending between the arms. Desirably these cross bar members may also be channel shaped and secured to said flanges 10^a and 12^a at their intermediate faces respectively, with their parallel arms extending downwardly.

It will be noted that the notches *n* are angularly disposed with respect to the side arms 10 and 12 so that when the side arms are clamped to the supporting surface the side arms will be inclined downwardly, and cross bar 16 will be below cross bar 14, thus positioning the device conveniently and so that it will require less space than would be the case if the mounted support means were to project at right angles to the supporting surface.

The device disclosed herein has the advantages of simplicity and low cost in manufacture, and may be readily and securely fastened onto support means widely varying in thickness.

It will thus be seen that there has been provided by this invention an apparatus in which the various objects hereinabove set forth together with many thoroughly practical advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

I claim:

1. A demountable support for towels and the like adapted to be secured to the apron of a washbowl or the like which comprises side arms stamped from sheet metal notched adjacent their rear ends, respectively, to receive said apron and each having a portion defining the front edge of said notch adapted to abut against the front face of said apron, and an inwardly extending end flange, cross bars secured to said side arms, and channel clamp members attached by screws to the said end flanges respectively, with the parallel sides of each channel member disposed on opposite sides of the arm to which it is attached and overlapping the notched portion of said side arm, said channel clamp members being adjustable toward or away from the said end flanges of said arms respectively to control the effective width of said notches and to engage the rear face of said apron at a plurality of places disposed on opposite sides of the engagement between the front face of said apron and the said portion of the front wall defining said notch.

2. A demountable support for towels and the like adapted to be formed from sheet metal stampings, comprising, side arms each having an inwardly extending flange at its rear end, and each having a notch extending downwardly from its upper surface in front of said end flange to receive a support means, cross bar means secured to said side arms, and clamp means for varying the width of said notches and for clamping said arms to said support member, said clamp means being adapted to straddle said end flanges respectively and to overlap the said notches in

which said support means is received, and means for supporting said clamp means on said end flanges respectively and for varying the extent each clamp means overlaps the notch of the side arm to which it is attached.

3. A demountable support for towels and the like adapted to be formed from sheet metal stampings, comprising, side arms each having an inwardly extending flange at its rear end, and each having a notch extending downwardly from its upper surface in front of said end flange to receive a support means, cross bar means secured to said side arms, and clamp means for varying the width of said notches and for clamping said arms to said support member, said clamp means being adapted to overlap the said notches in which said support means is received, and means for supporting said clamp means on said end flanges respectively and for varying the extent each clamp means overlaps the notch of the side arm to which it is attached.

4. A demountable support for towels and the like adapted to be formed from sheet metal stampings, comprising, side arms each having an inwardly extending flange at its rear end, and each having a notch extending downwardly from its upper surface in front of said end flange to receive a support means, cross bar means secured to said side arms, and clamp means for varying the width of said notches and for clamping said arms to said support member, said clamp means comprising channel members adapted to straddle said end flanges respectively with the side portions of said members extending forwardly and overlapping the said side arm notches respectively, said end flanges and the bridging portion of said clamp means being provided with threaded holes, and screw and nut means for supporting said clamps on said end flanges respectively so that each clamp may be moved toward and away from the end flange on which it is supported, to vary the width of said notch in the arm of which said end flange is a part.

5. A demountable support for towels and the like as claimed in claim 3 in which said end flanges are inclined with respect to the body of the side arms whereby said support will be inclined when it has been attached to said support means.

6. A demountable support for towels and the like as claimed in claim 3 in which the side arms each has an inwardly extending flange and the cross bar means is mounted to said side arms and secured to the flanges of said side arms.
